CALL RECORDER FOR TELEPHONE SYSTEMS

Original Filed June 17, 1926

FIG. 1

UNITED STATES PATENT OFFICE

ROBBINS TILDEN AND THOMAS A. TILDEN, OF HIGH POINT, NORTH CAROLINA

CALL RECORDER FOR TELEPHONE SYSTEMS

Application filed June 17, 1926, Serial No. 116,590. Renewed November 8, 1928.

This invention relates to electric signaling devices and has special reference to a call recorder whereby one telephone station may call a second station and record, at the 5 called station an indication, by dots, dashes, perforations or otherwise the number or characteristic of the station which has called.

In other words, the invention embodies means for receiving and making a permanent 10 record at a telephone station of the calls received from other stations and also indicating on such permanent record the station from which a call has been received, so that the user of the telephone station, in the event 15 of his or her absence therefrom, may upon their return, at once perceive not only the number of calls that have come in, but also the telephone numbers of the stations from which said calls have been made and the order 20 in which they have been made.

This device is preferable with automatic or machine switching equipment, that is, equipment that uses a calling device or other forms of impulse transmitters, senders or 25 circuit breakers on telephone stations for setting up and operating apparatus in a proper manner for connecting one station with any other station in the exchange or system, automatically, without the aid of human operators. 30

The purpose of the invention is to enable a telephone subscriber or station to call any other telephone subscriber or station in that particular city or system and register at the 35 called station, by means of dots, dashes or otherwise the number of the station calling. The device is preferably connected in parallel with the user's telephone as an extension, and using the same line as that connected to the 40 regular or main station.

The principle involved is to indicate on a suitable surface such as a strip of paper an impression disclosing, upon the receipt 45 of a telephone call, the number or other characteristic of the calling station. For instance, the telephone number of the calling station may be automatically printed or written in the form of code indications; these code indications may be in the form of dots or dashes. 50

For instance, the arrangement may be such

that a telephone numbered 3452 calling a station equipped with the device described herein will register on a strip or ribbon of paper, the proper number of marks and spaces, as hereafter explained in detail, which can be 55 readily interpreted to read 3452.

Long distance operators in the central office, or any other particular operator, employee or official of the telephone company could register their number by the machine 60 as in the same case of any regular calling telephone station. It could also be used in private systems, and could be used to replace complaint operators whose duties are to record telephones in trouble as subscribers report them. 65

The invention employs peculiar circuit arrangements which involve slight changes in the circuit of certain equipment (connectors) of the Strowger automatic equipment 70 and also of similar changes in other types of automatic or machine switching equipment. However, the changes made do not impair in the slightest degree the successful operation of such equipments nor does it take away 75 any of its particular features or improvements; nor do these minor changes effect transmission over its circuit, or complicate it to any noticeable extent. Such minor changes to be made by the operating telephone company only in the group or groups 80 having access to the lines connecting with the machine described herein.

It is noted that the use of this device is entirely under the control of the subscriber at 85 whose station it is installed. That is to say, it is not necessary to keep the device constantly connected in the line if the subscriber does not wish to do so. He may, by a suitable switch, connect the device for service 90 when he leaves his office or house and during his presence at such office or house may disconnect the same.

Business men in their offices, and any other class of men and women anywhere, 95 may leave their offices or other places equipped with this machine described herein and all incoming calls will be registered and recorded in a permanent form in their proper order, automatically, during their absence, 100

thus dispensing with, in many cases a clerk left merely to answer and record telephone calls.

The principal and most important objects of the invention are to provide an improved and novel construction of a device of this character to render the same, by improved means, capable of recording in a permanent manner code indications of the number of 10 a calling station; to improve and simplify the wiring of such a device; to provide an improved means in a device of this character for operating same by the regular operating exchange battery, thus eliminating any 15 local battery at subscriber's premises; to provide means for indicating back to the calling subscriber that he is connected with a station that has a device as described therein; and in general to provide a very simple, 20 reliable and highly efficient device; indicating on a permanent record the code numbers of all subscribers' stations calling his station.

With the above and other objects in view as will be hereinafter apparent, the invention 25 consists in general of certain novel details of construction and combination of parts hereinafter fully described, illustrated in the accompanying drawings and specifically claimed:

30 Figure 1 is a diagrammatic view of one form of the apparatus constructed in accordance with this invention.

Figure 2 shows a different arrangement 35 accomplishing the same result.

Fig. 3 shows a further modification applicable to the arrangements shown in Figs. 1 and 2.

In carrying out the objects of this invention, in Figure 1, there is provided an ordinary double pole switch or key 1 to which is 40 connected the line wires 2 and 3 leading to the particular subscriber's station. The telephone instruments themselves are not here shown as they do not enter directly into the invention, although certain parts of such instruments do co-operate with the invention, but as these parts are of well known forms 45 it has not been deemed necessary to show drawing thereof, the showing being restricted to a diagrammatic illustration. From this switch 1 leads a wire 4 which is 50 connected to one terminal of the winding of a relay coil 5, the other terminal of said relay coil being connected by a wire 6 with the condenser 7, connected with the other terminal of this condenser is a wire 8 leading to contact spring 9 of relay coil 5. There is also 55 provided another armature 10 which is held normally against stop 11 by the tension of spring 12; there is a bushing 13 for holding 60 down contact spring 9, so its contacts will remain in a make position as long as armature 10 is being energized by coil 5. The make contact 14 is connected by a wire 15 to 65 the condenser 7. This condenser 7 also has

another wire 16 leading to contact spring 17, which when in normal position makes contact with switch contact spring 18 and over wire 19 to one terminal of the winding of coil 20, thence over wire 21 to contact spring 22, which, when in its make position, establishes connection with contact spring 23, thence over wire 24 to the other terminal of coil 20, over wire 25 back to the double pole switch 1. Armature 26 operated by magnet 5 is normally held against adjustable stop 27 by tension of spring 28. At one end of the armature 26 is a recording means 29 arranged to press against tape 30 upon energization of magnet 5. The time wheel 31 meshes with wheels 32, 33 and 34, and carries a cam 35 arranged to trip releasing arm 36 at each complete revolution. This releasing arm carries an insulated bushing 37 at one end designed to break contact springs 38 and 18. At the other end of this releasing arm 36 is a dog 38, spring 39 holding releasing arm 36 normally against stop 40.

Two rubber feed rollers 41 and 42 are geared with the clock wheel mechanism 31, 32, 33 and 34, and rotate at a proper speed to guide and feed paper ribbon 30 from paper roll 43, past recording means 29. This end of paper ribbon 30 extends out and exposes to view the characters recorded thereon.

The operation of the apparatus as constructed in accordance with Figure 1 is as follows:

Switch or key 1 connects or disconnects the telephone number recording apparatus from the subscriber's line. If the key or switch is in the closed position (as is shown on drawing) ringing current from the central office or exchange intended to signal the called subscriber's bells, will attract the armature 9 of coil 5 over this circuit: Wire 2, switch 1, wire 25, coil 20, wire 19, contacts 18 and 17 in the normal or closed position, wire 16, condenser 7, wire 6, coil 5, wire 4, switch 1, and wire 3. Armature 9 is under very light spring tension, and will make with contact spring 14, during this ringing period. This will short out the condenser 7, over wire 8, contacts 9 and 14 and wire 15.

Shorting out this condenser will now cause the connector or similar equipment in central office to cut off the alternating ringing current and substitute direct current, or regular exchange battery current. Coil 5 will now attract armatures 10 and 26. Armature 10 carries an insulated bushing 13 which will press against and hold closed contacts 9 and 14. Armature 10 will catch in the dog 38 and thus remains until dog 38 is restored, regardless of any changes in the subscriber's line circuit or any variation or cessation in the current flowing through coil 5. Armature 10 releases wheel 32, which starts to rotate in the direction shown on drawing by arrow. Wheels 32, 33, 34 and 31, together with paper

thrust rollers 41 and 42, are all geared together and will start rotating from power furnished by coiled spring or other suitable means. Wheels 32 and 31 are geared together in such manner that they both make a complete revolution during the same period of time, so that always when wheel 31 is in the position shown on drawing; wheel 32 shall also be in the position shown.

5 This will permit wheel 32 and paper thrust rollers 41 and 42 to rotate for a short time after cam 35 on wheel 31 has caused bushing 37 to open springs 17 and 18 by means of the insulated bushing 37, thus causing an open 10 space to appear on the paper tape 30 showing the division between a complete operation of the device or the registration of a complete call number and also more readily permits the user to tear off and observe the code indications recorded thereon by thrusting the paper and indications out.

15 The speed of rotation of wheels 32, 33, 34 and 31, and the paper thrust rollers 41 and 42 is governed and is adjustable 20 so that the proper time for recording the number will elapse before the release of the machine as presently described, in order that the calling subscriber may have sufficient time to dial his own telephone number varying from 2 to 10 digits according to 25 the size of the exchange connected with. Cogs on wheel 34 will move spring 22 rapidly to close and open with contact 23. This will alternately short out coil 20, which will produce a distinctly audible and recognizable 30 tone back to the calling subscriber, notifying him that the station called has a machine of the character described herein and has connected itself and is ready to receive his number.

35 The calling subscriber, without restoring his receiver to the hook now proceeds to dial his own number. The calling device, impulse sender or contact breaker, on his telephone rapidly opens and closes the line circuit a number of times corresponding to the number dialled. If the dial is turned to 3, the circuit is opened three times; if to 7, then it will be opened seven times in rapid succession. These impulses originating at the 40 calling subscriber's calling device, and coming over the line to the called station will operate armature 26 of coil 5, moving this armature backward and forward in accordance with the number dialled. Armature 26 carries a recording means 29 which will make a 45 record of the number dialled on the strip of moving paper 30. This strip of paper 30 moves continuously and evenly across the recording means 29, speed governed and powered by suitable governor and clockwork, and this continuous, even movement will cause all short open spaces between the short dash marks or dots (these spaces representing the digit dialled) to be similar and easily interpreted. A short dash or dot will appear sep-

arating the open spaces that correspond to the digit recorded. For example: three short open spaces between long dashes represent the figure three. A long dash (many times longer than the short dash referred to above) will appear separating a digit of the complete call number. A long open space (many times longer than the short open space representing impulses forming the digit dialled) appearing on the paper denotes the division between complete call numbers. These long dashes separating digits of the call number and the long open spaces separating the complete call numbers are so much greater in length that no confusion could exist in distinguishing the code.

70 The next series of impulses coming over the line from the calling subscriber's dial, representing the second digit dialled, will be recorded on the moving paper tape 30 in like manner and so on until the calling subscriber has dialled his complete number. To illustrate this arrangement in a general way we will suppose Numbers 231 and 425 desire to record their numbers with this device, the 75 marks on the paper ribbon will be as follows:—

80 _____

85 The calling subscriber then restores his receiver to the hook. (If he fails to do so at this time, it will cause no confusion or trouble of any nature.) The wheels 32, 33, 34, 31 and the paper thrust rollers 41 and 42, continue to rotate until wheel 31 makes its complete revolution and cam 35 operates to restore dog 38 and open contacts 17 and 18. Armature 10, released by dog 38, restores to normal position, opening contacts 9 and 14, and in a short interval catches in stop cam of 90 wheel 32, preventing further rotation of wheel 32 and its associated clockwork, wheels 33, 34, 31 and rollers 41 and 42. Wheel 31 is timed in its relation to wheel 32 so that the restoring cam 35 on wheel 31 rotates far enough to permit dog 38 to rest against stop 95 40 or in the position shown on drawing. The recording device is now fully released and in normal or idle position, ready for another call to come in and be recorded. It will be noted that condenser 7, while readily permitting the passage of alternating current such as the ringing current intended to signal the called subscriber's bells, it opens the circuit with reference to direct current, exchange battery, or regular exchange operating current. There is sufficient impedance in coil 5 to not affect transmission of conversation over the subscriber's telephone, if he should accidentally leave the switch 1 in the closed position while he is present near the recording device, and desire to answer the telephone. Of course during his absence from the telephone, as previously explained he will leave switch 1 in the closed position.

This device may be connected to the line in such a manner that when the receiver hook is lifted to use the telephone, the recording device will be disconnected from the line.

If desired, wheel 34 or wheel 25, depending upon whether apparatus similar to that shown in Figure 1 or in Figure 2 is employed, could have a portion of its periphery beyond the point shown in contact with the tone generating springs, smooth or free from teeth in order that a few seconds could elapse before the tone was placed on the line back to the calling subscriber. This would permit the called subscriber to answer the telephone after his bells had rung once, provided he happened to be present and desired to do so, and yet had left his switch in the closed position as proper during his absence from the telephone.

If desired to work this device on metallic harmonic ringing party lines, armature 9 of relay coil 5, would be tuned to respond to a certain desired frequency only.

In Figure 2 which shows another form of the invention, wires 101 and 102 connect to the switch 103 and form the negative and positive of the subscriber's loop. From switch or key 103 a wire 104 is lead which is connected to one terminal of slow releasing relay coil 105. Another terminal of this coil connects over wire 106 with condenser 107 and with armature 108. From the other terminal of condenser 107 leads a wire 109 connecting with one terminal of winding on inkwriter coil magnet 110; the other terminal of this inkwriter magnet is connected by wire 111 to switch 103. Also connecting with condenser 107 is a wire 112 which leads to contact 113. From contact 114 is a wire 115 leading to contact 116 of relay 105. Relay coil 105 has a third terminal connected to wire 117 and to contact 118. Contact 118 operates to make with contact 119 and is connected by wire 120 to wire 104. Coil 105 operates dog 121 normally held against stop 122 by the tension of spring 123. Dog 121 is pivoted at 122a and is designed to catch in stop pin 124a of wheel 124. Wheel 125 carries a pinion 126 designed to mesh in the outer gear of wheels 124 and 127. Wheel 127 has affixed a cam or post 128 which operates at each revolution, movable arm 129 being normally held against stop 130 by the spring 131. This movable arm 129 carries a bushing 132 at one end for breaking contacts 113 and 114. Upon energization of inkwriter coil 110 armature 133 is pulled away from adjustable stop 134 and against tension of spring 135 causing recording means 136 to record on tape 137 the electrical impulses received. Two rubber faced rollers 138 and 139 are geared with the clock wheel mechanism 124, 125 and 127 and rotate at a proper speed to guide and feed paper ribbon 137 from paper roll 140, through recording

means 136. This end of paper ribbon 137 extends out and exposes to view the characters recorded thereon.

The operation of the invention in accordance with the apparatus shown in Figure 2 is as follows:

Switch or key 103 is used to connect or disconnect the recording device from subscriber's line 101 and 102. With this switch in the closed or make position, ringing current from the central office intended to signal the bells of the called party, energizes coil 105 attracting armature 108 (which is a very light armature under little tension) and moving same to connect with its make contact 116. Tracing this circuit from switch 103: Wire 111, winding of coil 110, wire 109, condenser 107, wire 106, winding of coil 105, wire 104, to switch 103. Armature 133 of coil 110 is under sufficient tension not to operate at this time with ringing current. When armature 108 makes with contact 116, a circuit is closed over wire 115, contact 114, and with movable arm 129 in normal position, contact 113, wire 112 and to wire 109, cutting off central office ringing current and causing connector or other apparatus in central office to furnish regular direct current exchange battery causing relay coil 105 and inkwriter magnet 110 to energize their armatures. At this period dog 121 releases wheel 124, also setting into motion wheels 125 and 127 and paper extracting rollers 138 and 139, which are operated by spring power or other suitable means. These wheels and rollers are geared to each other and are timed or speed regulated by governing means. Wheel 125 by teeth on its periphery causes impulse making spring 118 to make and brake contacts 118 and 119, thereby shorting out part of coil winding 105, over wires 117 and 120 causing a tone to be placed upon the line which tone is heard by the calling subscriber and thereby assuring him that the telephone station he has called has a device of the character described herein, and notifying him that such device is in readiness to receive and record his telephone number or code designation. Without hanging up, the calling party now proceeds to dial his own telephone number. These electrical impulses sent out from his impulse sender or calling device energizing and deenergizing coil 110 in accordance with these impulses and thereby causing armature 133 with its recording finger 136 to make suitable indications on tape 137. These indications on tape 137 are in the form of marks and spaces, and will always appear in a similar manner and are easily interpreted. Relay coil 105 being slow releasing does not respond to these impulses but will hold its armature 108 and releasing dog 121 in the energized position, allowing wheels 124, 125 and 127 and rollers 138 and 139 to continue their rotation. These wheels and

rollers are timed and wheel 127 carrying the cam post 128 will make one complete revolution in fifteen seconds, more or less, as required to dial from 2 to 10 digits in his call number, depending upon the size of the exchange. This is made adjustable to suit these conditions.

After the calling subscriber has dialled his own number, he will restore his receiver to the hook, clearing his line. The recording device releases and clears out any remaining apparatus participating in the connection as follows:

When cam post 128 moves arm 129 the circuit is opened at contacts 113 and 114, thereby deenergizing coil 105 and magnet 110 causing their armatures to restore to normal position and allowing releasing dog 121 to catch in tooth of wheel 124 a short time later to allow rollers 138 and 139 to rotate for an instant after recording finger 136 has restored; this causes an open space to appear on the tape separating complete call numbers and also more readily permits the user to tear off and observe the code indications recorded thereon by thrusting the paper indications out. This stops the rotation of the timing wheels and the recording tape, which are geared together.

If desired to work this device on ground ringing duplex lines, wire 106 from coil 105 would be connected to ground through a condenser.

Figure 3 shows how the recording finger may be attached to the armature in such manner as to mark or print on the paper ribbon when in the released, inactive or normal position. This arrangement is applicable to the apparatus as shown in Figure 1 or as shown in Figure 2.

In Figure 3, 201 is the magnet operating the recording means. 202 is an armature pivoted at 203 and normally held against adjustable stop 204 by the tension of spring 205. Attached to this armature 202 is a recording finger 206 which normally, or when magnet 201 is not excited, presses against paper ribbon 207. This paper ribbon is carried on a roll 208 and guided past the adjustable table 209 by rollers 210. The rubber faced rollers 211 and 212 rotate with the clock work and pull the paper ribbon 207 past recording finger 206 as well as guide and thrust the free end of paper out into clear view.

The operation of the recording device as shown in Figure 3 will differ from that shown and explained under Figures 1 and 2 only in the printing or marking on the paper ribbon. The marks and spaces appearing on the paper ribbon will be reversed in Figure 3. Marks will be substituted for spaces and spaces will be substituted for marks. To use the same example as previously selected: Suppose that Numbers 231 and 425 desire

to record their numbers with this device the marks on the paper ribbon will be as follows:

Since the mind and eye are usually trained to observe marks rather than the lack of them or spaces, it may be preferable to use this arrangement over that shown in Figures 1 and 2, as it may be more readily understood by the subscriber, though it will necessitate the obvious change in the ordinary commercial form of inkwriter or similar machine. Such machines are usually constructed to make an indication on the paper ribbon when the operating magnet is energized rather than deenergized as is the case with apparatus shown constructed with the Figure 3 modification. Since the equipment shown in Figure 3 is exactly like that previously explained in detail under explanations of Figures 1 and 2, it is not deemed necessary to repeat the operation in detail. This change in the construction of the recording mechanism will cause the recorded numbers to appear according to this method: The number of short dashes separated by short spaces in a series, will indicate the digit; a longer distinguishable open space will separate the digits in a call number; and a longer distinguishable dash mark will separate complete call numbers from each other.

A more elaborate arrangement combined with the special features shown in our application Serial Number 40,900 filed July 1, 1925, for Letters Patent in telephone call recorders, could be obtained by connecting a local battery or an additional source of battery and repeating impulses originating at the calling station, over a local circuit by an additional impulse repeating relay. Since this arrangement would still record the number of the calling station in the form of marks and open spaces instead of actual figures as shown in the application above referred to, it appears, on account of the greater simplicity and for economic reasons the device shown in Figures 1, 2 and 3 of this application is superior without additional battery, operating simply as an extension on the regular main telephone line.

It is obvious that minor changes may be made in the form and construction of the invention without departing from the material spirit thereof. It is not therefore desired to confine the invention to the exact form herein shown and described, but it is desired to include all such as properly come within the scope claimed. The expression "number of the calling telephone station," or similar expression, in the claims, is used as a brief expression to indicate the individual designation of the calling telephone station whatever that may be, whether numbers, words, letters or a combination of any or all

of these, or any other individual designation of a telephone that may be chosen.

What is claimed is:

1. In a common battery electro-mechanical switching telephone system having a regular exchange battery, means operated by the regular central office exchange battery for indicating the number characteristic of the calling telephone station at the called station, such number characteristic being shown in a similar manner by marks and open spaces on suitable material, and means for releasing the number indicating apparatus. 70
2. In a common battery electro-mechanical switching telephone system having a regular exchange battery, means operated by the regular central office battery for recording by a suitably powered inkwriter, marks and open spaces representing in a uniform code the number characteristic of the calling telephone station, at the called telephone station, and means for releasing the recording means. 75
3. In a common battery automatic electro-mechanical switching telephone system having a regular exchange battery and ringing current, means operated by the regular central office exchange ringing and battery current for recording the number of the calling telephone station at the called telephone station in the form of a uniform code of open spaces and marks on suitable material, and means for releasing the number recording means. 80
4. In a common battery electro-mechanical switching telephone system having a regular exchange battery and ringing current, means operated by the regular central office exchange ringing and battery currents for recording the number of the calling telephone station at the called telephone station, and means for informing the calling telephone station that the called station is equipped with a recording device and is in readiness to receive and record the number of the calling station. 85
5. In a common battery electro-mechanical switching telephone system having a regular exchange battery current, means operated by the regular central office exchange common battery current for recording the number of a calling telephone station at the called telephone station, and means operable after a suitable interval of time, for releasing said number recording apparatus. 90
6. In a common battery electro-mechanical switching telephone system having a regular exchange battery current, means operated by the regular central office exchange common battery current for recording the number of the calling telephone station at the called telephone station, and means operable after a predetermined interval of time for releasing said number recording device. 95
7. In a common battery electro-mechanical switching telephone system having a regular exchange battery current, means operated by the regular central office exchange common battery current for recording the number characteristic of the calling telephone station at the called telephone station, such number characteristic being shown at the called telephone station by marks and open spaces impressed on a suitable surface, and means for 100
- the regular central office exchange common battery current for recording the number of the calling telephone station at the called telephone station, means operable after a suitable interval of time for releasing said number recording apparatus, and means for automatically placing the line in condition to receive further calls and further access to the number recording device. 105
8. In a common battery electro-mechanical switching telephone system having a regular exchange battery current, means operated by the regular exchange battery current for recording at a called telephone station by a suitably powered inkwriter, marks and open spaces representing in a uniform code the number characteristic of a calling station, and means for setting the recording device into operation by use of the regular exchange ringing current. 110
9. In a common battery electro-mechanical switching telephone system having a regular exchange battery current, means operated by the regular central office exchange battery current for indicating the number characteristic of the calling telephone station at the called telephone station, such number characteristics being shown in a similar manner by marks and open spaces on a suitable material, and means for rendering the recorded number visible from the exterior of the recording device. 115
10. In a common battery electro-mechanical switching telephone system having a regular exchange battery current, means operated by the regular exchange battery current for recording at a called telephone station certain indicia representing the calling telephone station, and means for opening the circuit to the regular operating exchange battery current, but providing a path for alternating ringing current to set the recording device into operation. 120
11. In a common battery electro-mechanical switching telephone system having a regular exchange battery current, means operated by the regular central office exchange battery current for recording marks and open spaces representing the number characteristic of the calling telephone station at the called telephone station, and means for opening the circuit to the regular operating exchange direct current, but providing a path for alternating ringing current to set the recording device into operation. 125
12. In a common battery electro-mechanical switching telephone system having a regular exchange battery current, means operated by the regular exchange common battery current for indicating the number characteristic of the calling telephone station at the called telephone station, such number characteristic being shown at the called telephone station by marks and open spaces impressed on a suitable surface, and means for 130

providing distinguishable separation spaces between digits in a call number, and means for providing a more distinguishable separation space between complete call numbers.

- 5 13. In a common battery electro-mechanical switching telephone system having a regular exchange battery current, means operated by the regular central office exchange common battery current for indicating the
10 number characteristic of a calling telephone station at a called telephone station, such number characteristics being shown by marks and open spaces impressed on a suitable surface, and means for feeding the said suitable surface through the recording device at a governed uniform speed while the recording device is in operation to cause the indications thereon to constantly appear uniformly spaced with relation to each other.
- 15 14. In a common battery electro-mechanical switching telephone system having a regular exchange battery current, means operated by the regular central office exchange common battery current for recording by
20 means of a suitably powered inkwriter, marks and open spaces representing in a uniform code the number characteristic of a calling telephone station at the called telephone station, and means for connecting and disconnecting the recording device from the system.
- 25
- 30

In testimony that we claim the foregoing as our own we have signed our names to this specification.
